Patented June 19, 1962

193,071

PACKAGING TRAY

Gilbert R. Chadbourne, Oakland, Maine, assignor to Keyes Fibre Company, Portland, Maine, a corporation of Maine

Filed Apr. 7, 1960, Ser. No. 60,075

Term of patent 14 years

(Cl. D58—13)

FIG. 1 is a top plan view of a packaging tray embodying my new design;

FIG. 2 is a cross-sectional view taken along the line 2—2 of FIG. 1; and

FIG. 3 is a cross-sectional view taken along the line 3—3 of FIG. 1.

I claim:

The ornamental design for a packaging tray, as shown.
